GRINDING MACHINE AND METHOD

Alf Kristian Selnes, Detroit, Mich., assignor to
Ex-Cell-O Corporation, Detroit, Mich., a cor-
poration of Michigan

Application March 16, 1942, Serial No. 434,923

20 Claims. (Cl. 51—95)

The present invention relates generally to improvements in grinding machines and methods, and has particular reference to grinding machines, such for example as thread grinders, in which both the grinding wheel and the workpiece are rotated and are relatively translated in forward and return directions axially of the workpiece.

I have found that, in the use of grinding machines of the foregoing character, the quality of surface finish that is obtained, and the rate at which the stock can be removed without objectionable results, is influenced by the direction of rotation of the grinding wheel in relation to the direction of rotation of the workpiece. This relation is not always the same for different workpieces to obtain the best operating performance and quality of machining. Workpieces of certain classes can be ground most advantageously while rotating the grinding wheel and the workpiece in opposite directions. The stock is thereby removed in a climb cut in which the surfaces of the wheel and the workpiece travel in the same general direction at the point of contact. Included in this category are workpieces having relatively small diameters, or containing tungsten, or having a high degree of hardness, such as edge cutting tools, or requiring an uninterrupted cut, as in the relief grinding of taps. However, in grinding workpieces of other classes, such for example as aircraft cylinder barrels, and in general workpieces that have a relatively low degree of hardness or are relatively large in diameter, the best results are obtained by rotating the wheel and the workpiece in the same direction to perform a conventional cut in which the surfaces travel in opposite directions at the point of contact. More particularly, I have found that in grinding large workpieces at desirable speeds and feeds, a climb cut results in the exertion of a heavy pressure against the workpiece and attendant springing thereof, in the generation of excessive heat, and in objectionable discoloration of the ground surface due to burning, whereas a conventional cut permits the removal of the stock at a comparatively high rate without causing discoloration and other objectionable results.

One of the objects of the present invention, therefore, is to provide a novel grinding machine wherein the direction of rotation of the grinding wheel relative to that of the work is subject to convenient selective control at the will of the operator so that the grinding operation will be performed in a manner best suited to the particular requirements of each workpiece.

In grinding certain types of work, such as screw elements, the workpiece is commonly translated axially in forward and return directions relatively across the cutting periphery of the grinding wheel, and often a grinding cut is taken in both directions of translation so as to avoid an idle return stroke and thereby to save time. For any given direction and rate of relative translation, the direction and speed of rotation of the workpiece is determined by the hand and lead of the thread to be ground. Therefore, when grinding during both forward and return strokes, the work rotation must be reversed upon each reversal of translation so that the grinding wheel will follow the thread lead. This necessarily results in a reversal of the relative rotation between the grinding wheel and the workpiece if the wheel is rotated constantly in one direction as in conventional practice.

Another object of the present invention, therefore, is to provide a novel grinding machine and method of grinding in which a predetermined relative rotation between the grinding wheel and the workpiece is maintained regardless of reversal of the work rotation.

A more particular object is to provide a novel thread grinding machine and method in which the rotation of the grinding wheel is automatically reversed upon reversal of translation and rotation of the workpiece.

A further object is to provide a new and improved grinding machine of the foregoing character in which the workpiece is caused to dwell at the end of each cutting stroke to permit deceleration in the existing direction and then acceleration to normal speed in the reverse direction of the grinding wheel before initiating the reverse cutting stroke.

Another object is to provide a novel grinding machine and method in which the rotation of the grinding wheel is automatically reversed upon reversal of the work rotation while the wheel is out of contact with the workpiece.

Further objects and advantages will become apparent as the description proceeds.

In the accompanying drawings,

Figure 1 is a front elevational view of a grinding machine embodying features of my invention.

Fig. 2 is a plan view of the machine.

Fig. 3 is a diagrammatic representation of the electrical drive and control system used in the machine.

Fig. 4 is a front elevational view of a modified form of grinding machine embodying the invention.

Fig. 5 is a detail view of the feed mechanism for the grinding wheel in the machine of Fig. 4.

Fig. 6 is a diagrammatic representation of the hydraulic system used in the machine of Fig. 4.

Fig. 7 is a diagrammatic representation of the electrical drive and control system used in the machine of Fig. 4.

Figs. 8 and 9 are diagrammatic views illustrating the method of the invention respectively, with the work and the grinding wheel rotating in the same direction, and in opposite directions.

Machine structure

The present invention, although not limited thereto, is especially adapted for, and hence disclosed in connection with, the grinding of screw threads. One form of thread grinding machine embodying the invention is illustrated in Figs. 1 and 2. This machine is similar to the machine shown in a copending application by Harold N. Seyferth, Serial No. 350,338, filed August 3, 1940, and now Patent 2,317,226, to which reference may be had for a more detailed understanding of the specific structure.

The grinding machine, in the illustrated embodiment, comprises a base 10 supporting a horizontally translatable work slide or table 11. A headstock 12 is mounted on one end of the base 10, and includes a work drive shaft 13 which is rotatably anchored at its outer end through a bearing bracket 14 to the table 11 and which is adapted to be rotated and simultaneously translated axially in timed relation to the rotation to translate the table 11. Supported in the outer end of the shaft 13 is a live center 15. A tailstock 16 is adjustably mounted on the table 11, and has a dead center 17 in axial alinement with the center 15. The workpiece W to be ground is rotatably supported between the centers 15 and 17.

The drive for the work shaft 13 includes a reversible two-speed electric motor 18 mounted on one side of the base 10, and connected through a belt 19 to mechanism (not shown) within the headstock 12 for rotating the shaft and for translating the shaft axially under the control of a master lead screw (not shown). Upon rotation of the motor 18 in one direction, the shaft 13 will be driven to translate the table 11 to the right in an initial or forward cutting stroke, and the workpiece W will be rotated in a predetermined initial direction in timed relation to the translation as determined by the hand and lead of the screw thread to be ground. Upon rotation of the motor 18 in the opposite direction, the drive to the shaft 13 will be reversed to translate the table to the left in a return stroke and to rotate the workpiece W in the reverse direction.

A grinding wheel assembly 20 is mounted at the rear of the work table 11 on a cross slide 21 supported on the base 10 for movement transversely of the axis of the workpiece W. The assembly 20 includes a spindle 22 supporting a grinding wheel 23 and adapted to be driven through a belt 24 from a reversible electric motor 25. The slide 21 is adapted to be operated by a feed mechanism (not shown) to advance the grinding wheel incrementally toward the work for successive cuts to the desired depth, and to quickly retract the wheel from the work, if desired, at the end of each cutting stroke. The feed mechanism includes a hand wheel 26 and a retract lever 27 for controlling the setting of the grinding wheel, and a wheel 28 for controlling the size setting.

Coolant from a tank 29 is adapted to be supplied by a pump 30 through a duct 31 to the

grinding zone. The pump 30 is driven by an electric motor 32.

The various motors 18, 25 and 32 are connected in an electric system and are adapted to be operated in a predetermined manner to obtain an automatic machine cycle. A number of manually operable switches are included in the electrical control, and are mounted on a panel 33 adjacent the operator's station at the front of the machine.

Electrical control circuits and operation

Current is supplied for the various electric motors 18, 25 and 32 from three main supply lines 15 L₁, L₂ and L₃ adapted to be connected to a suitable source of three-phase alternating current. Two low voltage supply lines L₄ and L₅ for the control circuits proper are connected through a transformer 40 to the lines L₁ and L₃.

20 The coolant pump motor 32 is adapted to be connected to the main supply lines L₁, L₂ and L₃ by a starter having a set of normally open contacts P₁ adapted to be closed upon excitation of a relay coil P.

25 The wheel drive motor 25 is adapted to be connected to the main supply lines L₁, L₂ and L₃, to rotate the spindle 22 selectively in either direction, by a starter having two parallel sets of normally open contacts GF₁ and GR₁ adapted to be 30 alternately closed respectively upon selective excitation of relay coils GF and GR. Thus, when the coil GF is excited, the motor 25 will rotate in a forward direction, and when the coil GR is excited the motor will rotate in the opposite or 35 reverse direction.

35 The work drive motor 18 is adapted to be connected to the main supply lines L₁, L₂ and L₃ by a starter having two parallel sets of normally open contacts WF₁ and WR₁ adapted to be alternately closed upon selective excitation of relay coils WF and WR to translate and rotate the workpiece W alternately in forward and reverse directions. The starter also includes two additional parallel sets of normally open contacts S₁ and F₁ connected in series with the direction control contacts WF₁ and WR₁, and adapted to be closed selectively to control the speed of the motor 18. The contacts S₁ and F₁ are controlled respectively by two relay coils S and F adapted 45 to be connected selectively across the supply lines L₄ and L₅ under the control of two selector switches S₂ and S₃ and upon closing either of two contacts WF₂ and WR₂ under the control of the coils WF and WR. When the coil WF is excited, the contacts WF₂ will close a circuit through the switch S₂ either for the coil S or the coil F depending on the adjustment of the switch. Similarly, when the coil WR is excited, the contacts WR₂ will close a circuit through the switch S₃ either for the coil S or the coil F depending on the adjustment of this switch. Consequently, by selective adjustment, the motor 18 can be driven at either slow or fast speed in either direction as desired. Where a grinding cut is taken in both directions of work translation, both switches S₂ and S₃ are adjusted to close the circuit for the coil S, and the coil F is never excited, so that the motor 18 is driven at a slow speed in both directions of rotation.

70 The rotation of the motors 18 and 25 is adapted to be reversed automatically at each end of the work translation. The direction of rotation is under the control of a two-position limit switch LS₁ adapted for actuation by the table 11 alternately into opposite stations. During the for-

ward movement of the table 11, the limit switch LS₁ serves to complete a circuit across the supply lines L₄ and L₆ for a relay coil U. During the reverse direction, the limit switch LS₁ serves to complete a circuit for a relay coil L. The relay coils U and L form part of a latch relay LR which controls contacts LR₁ and LR₂ in the circuits for the coils GF and GR and contacts LR₃ and LR₄ in the circuits for the coils WF and WR. When the coil U is excited, the contacts LR₁ and LR₃ are closed and the contacts LR₂ and LR₄ are opened. When the coil L is excited, the contacts LR₁ and LR₃ are opened and the contacts LR₂ and LR₄ are closed. The contacts remain closed in each instance even though the coil in control thereof is deenergized by opening the switch LS₁ until the companion coil of the relay LR is energized.

Excitation of the coils P, GF and GR is under the control of a normally open starting push button switch S₄ and a normally closed stopping push button switch S₅. Interposed in the circuits for the coils GF and GR, in series with the contacts LR₁ and LR₂ is a manual selector switch S₆ which is adjustable to control the rotation of the grinding wheel 23 in relation to the rotation of the workpiece W. The switch S₆ is available to reverse the connections of the coils GF and GR in the circuits, so that in one station of the switch the grinding wheel and the workpiece will rotate in the same direction as illustrated in Fig. 8 to perform a conventional cut, and in the other station of the switch the wheel and the work will rotate in opposite directions as shown in Fig. 9 to perform a climb cut. If the master lead screw in the headstock 12 should be changed so as to have an opposite hand lead, it would be necessary to reverse the position of the switch S₆ in order to retain the desired relative rotation between the wheel and the workpiece.

Also interposed in the circuits for the coils GF and GR is a manual selector switch S₇ which in the station shown serves to place the coils under the selective control of the limit switch LS₁, and which, if adjusted into the opposed station, would connect the coil GF across the switch S₆ to effect rotation of the grinding wheel 23 constantly in one direction regardless of reversal of the table 11 and reversal of rotation of the workpiece W at each end of the table travel.

Assuming that the switch S₇ is adjusted to condition the system for automatic reversal of the grinding wheel upon reversal of the work rotation, and that the switch S₆ is adjusted to establish the desired direction of rotation of the wheel in relation to that of the work, operation is instituted by momentarily closing the switch S₄. This completes a circuit for the coil P from the supply line L₄ through the coil P, a line 41, the switch S₄, a line 42, the switch S₅, and a line 43 to the supply line L₆. Interposed in the line 43 is a master stop switch S₈ and a plurality of overload contacts 44. Excitation of the coil P serves to close the contacts P₁ to institute operation of the coolant motor 32, and also to close contacts P₂ to establish a holding circuit across the switch S₄.

With the limit switch LS₁ in the position shown, the contacts LR₁ are closed and the contacts LR₂ are opened. Consequently, closing of the switch S₄ serves also to establish a circuit for the coil GF from the supply line L₄ through the coil, a line 45, the switch S₆, a line 46, the contacts LR₁, a line 47, and the switch S₇ to the line 41. Excitation of the coil GF serves to close the contacts

GF₁ to institute rotation of the wheel drive motor 25 in a forward direction. If the switch S₆ had been adjusted into the opposed station, the coil GR instead of the coil GF would have been energized to institute rotation of the motor 25 initially in the reverse direction, the circuit leading from the supply line L₄ through the coil GR, a line 48, and the switch S₆ to the line 46. If the switch S₇ had been adjusted into the opposed station, the circuit for the coil GF would have been completed from the line 45 through a shunt line 49 across the switch S₈ to the line 41.

Upon reversal of the switch LS₁ at the end of the table movement in the forward direction, the coil U is deenergized and the coil L is energized, thereby opening the contacts LR₁ to interrupt the circuit for the coil GF and closing the contacts LR₂ to establish the circuit for the coil GR. Excitation of the coil GR serves to close the starter contacts GR₁, thereby reversing the direction of rotation of the motor 25 and consequently the rotation of the grinding wheel 23.

Operation of the motor 18 for translating and rotating the workpiece W reversibly is instituted by momentarily closing a manual switch S₉. This completes a circuit for a timing relay coil TR from the supply line L₄ through the coil, a line 50 including two normally closed parallel contacts RD₁ and RE₁, the switch S₉, a line 51 and a normally closed manual stop switch S₁₀ to the line 43. It also completes a parallel circuit from the line L₄ through a holding relay coil RA to the line 50. Excitation of the coil RA serves to close contacts RA₁ to complete a holding circuit for the coils TR and RA across the switch S₉. The contacts RD₁ and RE₁ are adapted to be opened respectively upon excitation of two relay coils RD and RE.

Excitation of the timing relay TR serves to close a switch TR₁, thereby connecting a line 52 from the starter coils WF and WR to the line 43. Two normally open contacts RD₂ and RE₂ are connected in series in a shunt line 53 across the switch TR₁. Since the contacts LR₃ are closed, the switch TR₁ will complete a circuit for the coil WF from the supply line L₄, through the coil, normally closed interlock contacts WR₃ controlled by the coil WR, a line 54, the contacts LR₃, the line 52 and the switch TR₁ to the line 43. The coil RD, being connected in parallel with the coil WF, is also excited, and opens the contacts RD₁ and closes contacts RD₂ and RD₃. Excitation of the coil WF serves to open interlock contacts WF₃ in the circuit for the coil WR, and to close the contacts WF₁ and WF₂. Closing of the contacts WF₂ serves to effect excitation of the coil S to close the contacts S₁. Consequently, operation of the motor 18 is instituted to rotate the workpiece W in a forward direction, as indicated by the full line arrow in Figs. 8 and 9, and to advance the table 11 in a forward direction. The grinding wheel 23 is also rotated in a forward direction, as indicated by the full line arrow in Fig. 8, so that the wheel and the work are rotated in the same direction and hence are moving oppositely at the point of contact to produce a conventional cut.

During the forward operation of the motor 18, a plugging switch 55 is actuated to open contacts PR and to close contacts PF. This establishes a circuit for the coil RE from the supply line L₄ through the coil, a line 56, normally open contacts WF₄ which are closed at this time by the coil WF, and the contacts PF to the supply line L₅. The coil RE serves to close contacts RE₃

across the contacts WF₄; also, to open the contacts RE₁ and to close the contacts RE₂. Consequently at this time, the coil TR is deenergized since the contacts RD₁ and RE₁ are both open, and causes the switch TR₁ to open. However, the starter circuit is maintained since the contacts RD₂ and RE₂ are both closed across the switch TR₁.

At the end of the forward cut, the switch LS₁ is actuated by the table 11 to interrupt the circuit for the coil U and to complete the circuit for the coil L, of the latch relay LR. As a result, the contacts LR₁ are opened and the contacts LR₂ are closed to effect reversal of the motor 25 so as to rotate the grinding wheel 23 in the direction indicated by the dotted arrow in Fig. 8. At the same time, the contacts LR₃ are opened to break the circuit for the starter coil WF, thereby effecting opening of the contacts WF₁ and WF₂ to interrupt the forward drive motor circuit. The circuit for the coil RD also is broken so that the contacts RD₁ are again closed and the contacts RD₂ are opened. The contacts LR₄ also are closed to condition the circuit for the coil WR from the line L₄ through the coil, the contacts WF₃ which are now closed, the line 56, and the contacts LR₄ to the line 52, but the circuit is not completed to the line 43 since the contacts RD₂ are open. However, a plugging circuit for the coil WR is completed from the line L₄ through the coil, the contacts WF₃, the line 56, the contacts RE₃, and the plugging contacts PF to the line L₅. Excitation of the coil WR serves to close the contacts WR₁ and WR₂, and the coil S serves to reclose the contacts S₁ to establish the reverse drive circuit for the motor 18. Thereupon, the motor 18 is plugged quickly to a standstill, the plugging circuit being maintained across or through the contacts PF as long as the motor continues to rotate in a forward direction.

When the motor 18 comes to a stop and starts to reverse, the plugging switch 55 is actuated to break the contacts PF, thereby interrupting the exciting circuit for the coils RE and WR. Deenergization of the coil RE opens the contacts RE₂ and recloses the contacts RE₁.

Since both contacts RD₁ and RE₁ are again closed, the circuit through the starting relay TR is reestablished across the manual starting switch S₈ since the coil RA has not been deenergized and has maintained the sealing circuit through the contacts RA₁. Excitation of the timing relay TR again closes the switch TR₁ to establish this time a circuit for the coil WR through the contacts LR₄. Excitation of the coil WR serves to open the interlock contacts WR₃ in the circuit for the coil WF and to close the contacts WR₁ and WR₂, thereby establishing the reverse drive circuit for the motor 18. The coil RE, being connected in parallel with the coil WR through the line 56, is also excited and serves to close the contacts RE₂ and RE₃ and to open the contacts RE₁. During reverse operation, the plugging contacts PR are closed to complete a circuit for the coil RD through the contacts WR₄. Excitation of the coil RD serves to close the contacts RD₂ and RD₃ and to open the contacts RD₁. Since the contacts RD₁ and RE₁ are now both open, the coil TR is deenergized to open the switch TR₁, but the circuit for the coils RE and WR is maintained through the contacts RD₂ and RE₂.

A cutting stroke is now obtained during the return movement of the slide 11. During this re-

turn movement, the rotation of the workpiece W is reversed, but the rotation of the grinding wheel 23 is also reversed so that the wheel and the work still rotate in the same direction as indicated by the dotted arrows in Fig. 8. At the end of the return movement, the foregoing cycle of control can be repeated to condition the machine for another cut in the forward direction, or the operation can be stopped by opening the switch S₈.

It will be noted that at each end of the table travel, the reversal of the table drive is delayed to provide a dwell during which the grinding wheel 23 is decelerated in the prevailing direction of rotation, and then accelerated to full speed in the opposed direction of rotation. In other words, the workpiece W is not translated while reversal of the grinding wheel 23 is being effected.

In some instances, it may be desirable to leave the grinding wheel in contact with the work while effecting reversal so as to loosen any glazed grains and to sharpen the surface of the wheel. However, in other instances, it is preferable to effect reversal of the grinding wheel 23 while out of contact with or retracted from the workpiece W. To this end, a solenoid RC is adapted to be connected across the main supply lines L₁ and L₃ by two contacts RB₁ and RB₂ under the control of a relay coil RB connected across the lines L₄ and 52. When the starting circuit for either of the coils WF and WR is established across the switch TR₁, the coil RB will be excited to close the contacts RB₁ and RB₂. As a result, the solenoid RC will be actuated to advance the grinding wheel 23 into operative position. Upon interrupting the circuit from the line 52 to the line 43 at each end of the table travel, the coil RB is deenergized to open the contacts RB₁ and RB₂. Thereupon, the solenoid RC is disconnected to effect retraction of the grinding wheel 23 from the workpiece W and it is in this retracted position that the rotation of the grinding wheel is reversed.

Hydraulic machine structure

The thread grinding machine disclosed in Figs. 4 to 7 also embodies the features of the invention, but instead of being fully electrically driven and controlled like the machine of Figs. 1 to 3, it utilizes a reversible, variable speed rotary hydraulic motor for rotating and translating the work, and has a combined hydraulic and electric control. Apart from the specific control, the machine is substantially like that disclosed in United States Letters Patent No. 2,251,961, issued August 12, 1941, to Ira J. Snader, to which reference may be had for a more detailed understanding of the mechanical structure.

Referring to Figs. 4 and 5, the machine comprises a base 60, and a work table 61 reciprocable thereon. A headstock 62 is supported on one end of the table 61, and encloses a work spindle 63 having a live center 64. Adjustably mounted on the table 61 in spaced relation to the headstock 62 is a tailstock 65 having a dead center 66 in axial alignment with the center 64. It will be understood that the workpiece (not shown) is adapted to be operably supported by the centers 64 and 66.

The work spindle 63 is adapted to be driven by a reversible, variable speed rotary hydraulic motor 67 mounted within the headstock 62 and connected through a belt 68 to a mechanical drive mechanism 69. The work table 61 is adapted to

be translated in opposite directions and in timed relation to the rotation of the spindle 63 by a nut and screw drive (not shown) within the base 60 and connected to the spindle drive mechanism 69. Pressure fluid for operating the motor 61 is supplied by a pump 70 mounted at the rear of the base 60, and driven by an electric motor 71. One end of the nut and screw drive for the table 61 is connected to a backlash compensator 72 having a hydraulic cylinder 73 and an actuating piston 74 anchored to a shaft extension 75 of the screw.

Mounted on the rear of the base 60 is a grinding wheel assembly 76 including a spindle structure 77 driven by a reversible electric motor 78 and supporting a grinding wheel 79. The spindle structure 77 is mounted on a cradle 80 on a cross slide (not shown) movable toward the workpiece to feed the grinding wheel 79 step by step into the work to final depth in timed relation to successive cutting strokes of the table 61. The cross feed is actuated a predetermined distance at each reversal of the table 61, and includes a feed screw 81 operatively connected to the cross slide and provided with a hand wheel 82.

A hydraulic feed mechanism is provided for automatically actuating the screw 81. In the present instance, the feed mechanism (see Fig. 5) is operated by a hydraulic actuator 83 having a cylinder 84 in which a double end piston 85 is reciprocable. The piston 85 is formed intermediate its ends with a longitudinal gear rack 86 meshing with a pinion 87 and adapted in each stroke to rotate the latter through one complete revolution. A disk 88 is fixed for rotation with the pinion 87, and carries an eccentric crank pin 89 connected to one end of an adjustable rod 90. The other end of the rod 90 is formed with a gear rack 91 meshing with a pinion 92 in turn in engagement with a gear segment 93. A feed pawl 94 is revolvable with the segment 93, and is arranged for engagement with a ratchet 95 operatively connected to the cross feed screw 81. The depth of cut during each grinding stroke is controlled by an adjustable shield 96 arranged to lift the pawl from the ratchet 95 during a portion of each pawl stroke.

Associated with the cross feed mechanism is a hydraulic actuator 97 available to locate the grinding wheel 79 in operative position during the grinding cut, and on occasion to retract the wheel from the work. The actuator 97 comprises a cylinder 98 enclosing a reciprocator piston 99.

Associated with the grinding wheel 79 is a suitable dressing mechanism having one or more tools (not shown) movable by a reversible electric motor 100 back and forth in a dressing cycle across the cutting periphery of the grinding wheel 79, and having a hydraulic actuator 101 for advancing the tools toward the wheel in a dressing feed. The actuator 101 comprises a cylinder 102 and an operating piston 103 reciprocable therein.

Coolant is adapted to be supplied to the grinding zone through a duct 104 from a pump (not shown) driven by an electric motor 105.

Hydraulic system

The machine comprises a hydraulic control system (see Fig. 6) including a series of electro-magnetically operated valves for selectively controlling the supply of pressure fluid from the pump 70 to the various hydraulic actuators 61, 72, 83, 97 and 101.

The pump 70 has an inlet line 106 taking fluid from a supply tank 107, and has a pressure delivery line 108 connected to a main control valve 109 for the hydraulic motor 67. The pump 70 is of the variable delivery type, such for example as disclosed in a copending application Serial No. 147,178 filed June 9, 1937, by Ira J. Snader and Max A. Mathys, and has a volume control line 110 for varying the displacement in accordance with the requirements of the motor 67.

The main valve 109 is of the three-position type, and has a plunger 111 normally urged by spring pressure into the intermediate position. The ends of the valve plunger 111 are operatively connected respectively to two operating solenoids SO₁ and SO₂. Upon excitation of the solenoid SO₁, the plunger 111 will be shifted into the left end position to connect the pressure line 108 to a line 112 leading to one side of the hydraulic motor 67 and to connect a line 113 from the other side of the motor to an exhaust line 114. Upon excitation of the solenoid SO₂, the plunger 111 will be shifted into the opposite end position to reverse the connections for the lines 112 and 113, thereby effecting reversal of the motor 67. In the neutral position, which obtains when both solenoids are deenergized, the plunger 111 blocks both lines 112 and 113 to stop the motor 67. The valve plunger 111 also serves when in either end position to connect the pump control line 110 to the exhaust line 114, and when in neutral position to connect the control line through a passage 115 to the pressure line 108. When the exhaust pressure is relatively low, the pump 70 will deliver a correspondingly large volume of fluid to operate the motor 67 at a rapid rate. When the exhaust pressure is relatively high, the pump 70 will deliver a correspondingly small volume of fluid to operate the motor 67 at a slow rate. When the pressure line 108 is connected to the control line 110, the pump delivery is at a minimum and merely enough to maintain the normal working pressure.

The displacement of the pump 70, and hence the operating speed of the motor 67, therefore is under the control of the exhaust pressure. To effect desired variations in the operating speed of the hydraulic motor 67, a plurality of adjustable restricted flow orifices 116, 117 and 118, discharging through a drain line 119 to the tank 107, are arranged for selective connection with the exhaust line 114 under the control of an orifice selection valve 120.

The orifice selection valve 120 comprises a shiftable three-position plunger 121 operatively connected at opposite ends respectively to two actuating solenoids SO₃ and SO₄, and normally urged into neutral position by spring pressure. In the neutral position of the plunger 121, the exhaust line 114 is connected through a passage 122 in the plunger to the orifice 117. Upon excitation of the solenoid SO₃, the plunger 121 is shifted into the left end position to connect the exhaust line 114 to the orifice 116. Upon excitation of the solenoid SO₄, the plunger 121 is shifted into the right end position to connect the exhaust line 114 to the orifice 118. By selective adjustment of the orifice restrictions, different back pressures can be obtained in the exhaust line 114 so that the work table 61 can be translated, for example, with a rapid approach, a slow cutting rate in one direction, and the same or a different slow cutting rate in the opposite direction.

A series of auxiliary control valves 123, 124,

125 and 126 are provided for respectively controlling the actuators 12, 83, 97 and 101. Each of these valves has a pressure connection with an auxiliary pressure line 127 supplied with fluid through a pressure reducing valve 128 from the main pressure line 108. The valve 128 is operative to maintain a substantially constant predetermined low pressure in the line 127. In the event of a pressure drop in the line 127, the valve 128 will admit additional make-up fluid thereto from the line 108. In the event of a pressure rise in the line 127, the valve 128 will spill excess fluid therefrom to the drain line 119. The backlash compensator valve 123 is of the two-position type, and has a plunger 129 connected at opposite ends respectively to two actuating solenoids SO₅ and SO₆. In one position, the plunger 129 will connect the pressure line 127 through a line 130 to one end of the cylinder 73. In the other end position, the plunger 129 will connect the line 127 through a line 131 to the other end of the cylinder 73. In each position of the valve 123, the line receiving fluid dispensed by the piston 74 is connected to the drain line 119.

The wheel feed control valve 124 is also of the two-position type, and has a plunger 132 connected at opposite ends respectively to two actuating solenoids SO₇ and SO₈. Upon excitation of the solenoid SO₇, the plunger 132 will be shifted into one end position to connect the pressure line 127 through a line 133 to one end of the wheel feed cylinder 84 and to connect the other end of the cylinder through a line 134 to the drain line 119. Upon excitation of the solenoid SO₈, the connections for the lines 133 and 134 will be reversed.

The retract valve 125 is of the two-position type, and has a plunger 135 normally located in a stop position by a spring 136 to connect the pressure line 127 through a line 137 to one end of the retract cylinder 98, and to connect the other end of the cylinder through a line 138 to the drain line 119. The plunger 135 is connected to an actuating solenoid SO₉ which, when energized, will shift the plunger against the action of the spring 136 to reverse the connections for the lines 137 and 138. When the solenoid SO₉ is energized, the grinding wheel 79 is advanced into cutting position, and when the solenoid is deenergized, the wheel is retracted from the work.

The dresser feed valve 126 is similar to the valve 125, and comprises a plunger 139 normally held in a stop position by a spring 140 to connect the pressure line 127 through a line 141 to one end of the dresser feed cylinder 102, and to connect the other end of the cylinder through a line 142 to the drain line 119. The plunger 139 is connected to an actuating solenoid SO₁₀ which when energized will shift the plunger to reverse the connections for the lines 141 and 142.

Electrical control circuits and operation

The grinding wheel motor 78 and the coolant pump motor 105 correspond to the motors 25 and 32 of Fig. 3. These motors of the two machines have the same circuits and controls, and hence the corresponding relay coils, switches and contacts are identified by the same reference characters.

The hydraulic pump motor 71 is adapted to be connected to the main L₁, L₂ and L₃ by normally open contacts H₁ adapted to be engaged upon excitation of a relay coil H by closing a manual starting switch Sw1. The circuit is completed

over a master stop switch Sw2. Energization of the coil H serves to close holding contacts H₂ across the switch Sw1. The contacts H₂ are located in the line L₅ so that if the pump motor 71 is not conditioned for operation, the entire system is disabled.

To institute the machine cycle, a manual switch Sw3 is closed momentarily to connect a relay coil C over the normally closed stop switch Sw4 across the main supply lines L₄ and L₅. Excitation of the coil C closes contacts C₁, C₂ and C₃. The contacts C₂ serve to connect a relay coil D over limit switch LS₅ across the supply lines L₄ and L₅. Excitation of the coil D closes contacts D₁, D₂ and D₃ and opens contacts D₄ and D₅. Contacts C₁ and D₁ establish a holding circuit across the switch Sw3 for the coils C and D, and the contacts D₂ establish an additional holding circuit across the contacts C₂ for the coil D.

Since contacts U₁ have been closed by the coil U, while contacts L₁ remain open, closing of the contacts C₃ and D₃ serves to connect the solenoid SO₇ across the supply lines L₄ and L₅, thereby adjusting the valve 124 to impart a forward feed to the grinding wheel. If the coil L has been energized instead of the coil U, the solenoid SO₈ would have been energized by closing the contacts L₁ to effect the approach feed.

The retract solenoid SO₉ is adapted to be connected in parallel with the selected one of the starting solenoids SO₁ and SO₂ for the hydraulic motor 61. A selector switch Sw5 is adjustable to effect energization of the solenoid SO₉ either during the forward travel or during the return travel of the work table, or during the travel of the table in both directions, with merely a temporary tool retraction at the end of each stroke. The switch Sw5 controls the connection of the solenoid SO₉ through two parallel contacts U₂ and U₃ adapted to be actuated by the coil U. The contacts U₂ are normally open and the contacts U₃ are normally closed. In one adjustment of the switch Sw5, both of these contacts are interposed in the circuit so that the solenoid SO₉ will be energized regardless of whether or not the coil U is energized or deenergized. In another adjustment of the switch Sw5, only the contacts U₃ are interposed in the circuit, and in this event the solenoid SO₉ is deenergized during the forward travel and energized during the return travel of the table. In a third adjustment of the switch Sw5, only the contacts U₂ are interposed in the circuit, and in this event the solenoid SO₉ is energized during the forward travel and deenergized during the return travel of the table.

At the end of the cross feed movement, a cam lobe 143 on the disk 88 (Fig. 5) serves to close a limit switch LS₄, thereby completing a circuit for a relay coil E and the solenoids SO₁ and SO₆, from the line L₄ through interlock contacts F₁, the contacts U₄ now closed by the coil U, and the switch LS₄ to the line L₅. Simultaneously, the circuit is closed for the retract solenoid SO₉ to advance the grinding wheel 79 into operative position. The solenoid SO₁ serves to adjust the main valve 109 out of neutral into the approach position, and the solenoid SO₆ serves to adjust the valve 123 to actuate the backlash compensator in the proper direction. At this time, the circuit for the solenoid SO₃ is closed through normally closed contacts G₂, and hence the selection valve 120 is adjusted to connect the orifice 116 in the exhaust line 114.

At the end of the approach, the table 61 closes a limit switch LS₂ to energize a relay coil G. Ex-

citation of the coil G serves to close contacts G₁ in the circuit for the solenoid SO₂, and to open the contacts G₂, thereby effecting adjustment of the valve 120 into neutral to connect the feed orifice 117 in the exhaust line 114. The motor 67 now operates in the forward direction at a relatively low feed rate in accordance with the setting of the orifice.

At the end of the grinding stroke in the forward direction, the limit switch LS₁ is actuated to effect deenergization of the relay coil U and energization of the relay coil L. Thereupon, the contacts U₁, U₂, U₄ are opened, and the contacts U₃ and L₁ to L₄ are closed. This closes a circuit for the coil F and the solenoids SO₂ and SO₅ from the line L₄ through interlock contacts E₁, contacts L₂ and contacts G₁ to the switch LS₄. Excitation of the solenoid SO₂ serves to reverse the valve 109 to reverse the direction of rotation of the motor 67, and excitation of the solenoid SO₅ serves to reverse the valve 123 to reverse the backlash compensator. Also, the solenoid SO₇ is deenergized and the solenoid SO₈ is energized to impart a forward feed increment to the grinding wheel. Upon initiation of the feed increment, the limit switch LS₄ is opened to interrupt the reversal of the table 61 until the feed movement is completed. During the dwell occasioned by the wheel feed, the solenoid SO₉ is deenergized to retract the wheel and the wheel motor 78 is reversed.

The grinding wheel may be dressed at any convenient time. To start the dressing operation, the hand switch Sw₆ is closed, thereby completing a circuit for the solenoid SO₁₀ and the relay coil K through the normally closed stop switch Sw₇. The solenoid SO₁₀ actuates the valve 126 to impart a forward feed of the dressing mechanism toward the grinding wheel. The coil K closes holding contacts K₁ across the switch Sw₆.

At the end of the dresser feed, a limit switch LS₃ is closed to complete a circuit for a coil DF, from the main line L₄ through limit switch LS₆, the coil DF, normally closed interlock contacts DR₂, the switch LS₃, and the switch Sw₇ to the main line L₅. Excitation of the coil DF serves to close starter contacts DF₁ in the circuits for the dresser motor 100, thereby energizing a brake solenoid 144 to release the motor brake and causing the motor to operate in a forward direction. At the end of the forward movement, the limit switch LS₆ is opened, and the limit switch LS₇ is closed to deenergize the coil DF and energize a coil DR. The coil DR opens contacts DR₃ to open the circuit for the solenoid SO₁₀ so as to impart an additional dresser feed, and closes the motor contacts DR₁ to reverse the rotation of the dresser motor 100. At the end of the cycle, the switch Sw₇ is opened to interrupt the dressing operation.

The work table continues to reciprocate back and forth to take successive grinding cuts until the work is ground to the desired depth. Thereupon, the limit switch LS₅ is opened to interrupt the circuit for the coil D. The table will continue to move until it reaches the end of the stroke, whereupon either the contacts E₃ or F₃ are opened to break the circuit for the coil C to stop the machine operation.

I claim as my invention:

1. A grinding machine comprising, in combination, means including a work spindle for supporting a workpiece for rotation about a fixed axis and in a predetermined direction, a grinding spindle having a grinding wheel mounted for peripheral cutting engagement with the workpiece, and

drive means for rotating said spindles, said drive means including control means for reversing the rotation of said grinding spindle, whereby said grinding wheel may be caused to rotate selectively in either the same or opposite direction relative to the rotation of the workpiece.

2. A grinding machine comprising, in combination, means including a work spindle for supporting a workpiece for rotation about a fixed axis, drive means operable to rotate the workpiece selectively in either direction, means for supporting said spindle for translation in timed relation to the spindle rotation, a grinding spindle having a rotary grinding wheel arranged for peripheral cutting engagement with the workpiece, drive means for rotating said grinding spindle, and control means for automatically reversing said last mentioned drive means to effect reversal of the rotation of said grinding spindle upon reversal of the translation and rotation of said work spindle, said control means including selector means for determining the direction of rotation of said grinding spindle relative to the direction of rotation of said work spindle.

3. A grinding machine comprising, in combination, means including a work spindle for supporting a workpiece for rotation about a predetermined axis, drive means for rotating said workpiece selectively in either direction, means for supporting said spindle for translation in timed relation to the spindle rotation, a grinding spindle having a grinding wheel mounted for peripheral cutting engagement with the workpiece, reversible drive means for rotating said workpiece selectively adjustable to effect rotation of said grinding wheel constantly in one direction or the other or to effect automatic reversal of the rotation of said grinding wheel upon reversal of the translation and rotation of the workpiece.

4. A grinding machine comprising, in combination, means supporting a workpiece for rotation, drive means for rotating said workpiece selectively in either direction, a grinding spindle having a grinding wheel mounted for cutting engagement with the workpiece, reversible drive means for rotating said spindle, and control means selectively adjustable to effect rotation of said grinding wheel in one direction or the other relative to the rotation of the workpiece, and operable to effect automatic reversal of the rotation of said grinding wheel upon reversal of the rotation of the workpiece.

5. A method of grinding rotary workpieces with a rotary grinding wheel which consists in positively rotating the workpiece in a predetermined initial direction and simultaneously rotating the grinding wheel in a predetermined initial direction relative to the workpiece with said grinding wheel and workpiece in peripheral cutting engagement, translating said workpiece axially in a given direction in timed relation to the rotation of said workpiece, reversing the translation and rotation of the workpiece, and automatically reversing the rotation of the grinding wheel upon reversal of rotation of the workpiece, whereby to maintain the preselected rotary cutting relationship between said wheel and the workpiece.

6. A method of grinding rotary workpieces with a rotary grinding wheel which consists in positively rotating the workpiece in a predetermined initial direction and simultaneously rotating the grinding wheel in the same direction with said grinding wheel and workpiece in peripheral cutting engagement, translating said workpiece ax-

ially in a given direction in timed relation to the rotation of said workpiece, reversing the translation and rotation of the workpiece, and automatically reversing the rotation of the grinding wheel upon reversal of rotation of the workpiece, whereby to maintain the preselected rotary cutting relationship between said wheel and the workpiece.

7. A method of grinding rotary workpieces with a rotary grinding wheel which consists in positively rotating the workpiece in a predetermined initial direction and simultaneously rotating the grinding wheel in a direction opposite to the rotation of the workpiece with said grinding wheel and workpiece in peripheral cutting engagement, translating said workpiece axially in a given direction in timed relation to the rotation of said workpiece, reversing the translation and rotation of the workpiece, and automatically reversing the rotation of the grinding wheel upon reversal of rotation of the workpiece, whereby to maintain the preselected rotary cutting relationship between said wheel and the workpiece.

8. A grinding machine comprising, in combination, a base, a spindle mounted on said base and supporting a rotary grinding wheel, a reversible electric motor for driving said spindle, a work table for supporting a rotary workpiece and mounted on said base for reciprocation axially of the workpiece through cutting engagement with the grinding wheel, means including a reversible electric motor for translating said table and for rotating the workpiece in timed relation to the translation, and electric control means operable by said table at one end of said translation to effect reversal of both of said motors, whereby to maintain a preselected relative rotation between said grinding wheel and the workpiece during rotation of the workpiece in the initial direction and subsequent rotation of the workpiece in the reverse direction respectively for the forward and return cutting strokes of said table.

9. A grinding machine comprising, in combination, a base, a spindle mounted on said base and supporting a rotary grinding wheel, a reversible drive means for said spindle, a work table for supporting a rotary workpiece and mounted on said base for reciprocation axially of the workpiece through cutting engagement with the grinding wheel, reversible drive means for translating said table and for rotating the workpiece in timed relation to the translation, and control means operable by said table at one end of said translation to effect reversal of both of said drive means, whereby to maintain a preselected relative rotation between said grinding wheel and the workpiece during rotation of the workpiece in the initial direction and subsequent rotation of the workpiece in the reverse direction respectively for the forward and return cutting strokes of said table.

10. A grinding machine comprising, in combination, means for supporting a workpiece for timed rotation and translation in forward and return directions, a spindle supporting a grinding wheel mounted for cutting engagement with said workpiece, and means automatically operable upon translation of said workpiece into a predetermined position to effect concurrent reversal in the rotation of the workpiece and said grinding wheel.

11. A grinding machine comprising, in combination, means supporting a workpiece for rotation and for translation in timed relation to the rotation, drive means for said workpiece automatically operable to effect reversal of said translation

and substantially concurrent reversal of rotation of the workpiece, a grinding spindle supporting a grinding wheel for cutting engagement with the workpiece in both directions of translation of the workpiece, drive means for rotation said spindle, and control means for said drive means, whereby said spindle may be rotated selectively either in one direction or the other relative to the direction of rotation of the workpiece and operable to maintain the preselected relative rotation between said grinding wheel and the workpiece regardless of reversal of rotation of the workpiece.

12. A grinding machine comprising, in combination, means supporting a workpiece for rotation and for translation in timed relation to the rotation, drive means for said workpiece automatically operable at a predetermined point in said translation to effect reversal of said translation after a dwell period and a reversal of rotation of the workpiece during said period, a grinding spindle supporting a grinding wheel for cutting engagement with the workpiece in both directions of translation of the workpiece, drive means for rotating said spindle, and control means for said last mentioned drive means automatically operable during said dwell period to effect reversal of rotation of said grinding wheel.

13. A grinding machine comprising, in combination, means supporting a workpiece for rotation and for translation in timed relation to the rotation, drive means for said workpiece automatically operable to effect reversal of said translation and timed reversal of rotation of the workpiece, a grinding spindle supporting a grinding wheel for cutting engagement with the workpiece in both directions of translation of the workpiece, drive means for rotating said spindle, and control means for said drive means automatically operable upon reversal of said work translation and rotation to separate said wheel temporarily from the workpiece and during such separation to reverse the rotation of said wheel.

14. A grinding machine comprising, in combination, means supporting a workpiece for rotation and for translation in timed relation to the rotation, drive means for said workpiece automatically operable at the end of said translation in one direction to effect reversal of said translation after a dwell period and a reversal of rotation of the workpiece during said dwell period, a grinding spindle supporting a grinding wheel for cutting engagement with the workpiece in both directions of translation of the workpiece, drive means for rotating said spindle, and control means for said drive means automatically operable during said dwell period to separate said wheel temporarily from the workpiece and during such separation to reverse the rotation of said wheel.

15. A method of grinding rotary workpieces comprising translating the workpiece axially in an initial direction and positively rotating the workpiece in timed relation to the translation in an initial direction, rotating the grinding wheel in a predetermined initial direction while in peripheral cutting engagement with the workpiece during the initial cutting stroke, stopping the translation of the workpiece with a dwell at the end of said translation in the initial direction, reversing the direction of rotation of the workpiece and of said grinding wheel during said dwell, and translating the workpiece axially in a return stroke through cutting engagement with the grinding wheel.

16. A method of grinding rotary workpieces comprising translating the workpiece axially in

an initial direction and rotating the workpiece in timed relation to the translation in an initial direction, rotating the grinding wheel in a predetermined initial direction while in engagement with the workpiece during the initial cutting stroke, stopping the translation of the workpiece with a dwell at the end of said translation in the initial direction, retracting said grinding wheel from the workpiece during said dwell, reversing the direction of rotation of the workpiece and of said grinding wheel during said dwell, returning said grinding wheel into cutting position, and translating the workpiece axially in a return stroke through cutting engagement with the grinding wheel.

17. A method of grinding rotary workpieces comprising translating the workpiece axially in an initial direction and rotating the workpiece in timed relation to the translation in an initial direction, rotating the grinding wheel in a predetermined initial direction while in engagement with the workpiece, reversing the direction of rotation of the workpiece and of said grinding wheel at the end of said initial translation, and then translating the workpiece axially in a return direction through cutting engagement with the grinding wheel.

18. A method of grinding rotary workpieces comprising translating the workpiece axially in an initial direction and rotating the workpiece in timed relation to the translation in an initial direction, rotating the grinding wheel in a predetermined initial direction while in engagement with the workpiece, automatically reversing the

direction of rotation of the workpiece and of said grinding wheel at the end of said initial translation and then automatically translating the workpiece axially in a return direction through cutting engagement with the grinding wheel.

- 5 19. A grinding machine comprising, in combination, means for supporting a workpiece for timed rotation and translation in forward and return directions, a spindle for supporting a grinding wheel mounted for cutting engagement with the workpiece, and control means automatically operable upon translation of said workpiece into a predetermined position to effect reversal in the rotation of both the workpiece and the grinding wheel, said control means including manual means selectively available at will to cause said wheel to rotate either in the same direction or the opposite direction relative to the direction of rotation of the workpiece.
- 10 20. A grinding machine comprising, in combination, means for supporting a workpiece for timed rotation and translation in forward and return directions, drive means including a reversible hydraulic motor for said workpiece and being automatically operated to effect reversal of said translation and timed reversal of the rotation of said workpiece, a spindle supporting a grinding wheel mounted for cutting engagement with said workpiece, and electric control means automatically operable upon translation of said workpiece into a predetermined position to effect substantial concurrent reversal in the rotation of the workpiece and said grinding wheel.
